UNITED STATES PATENT OFFICE.

ERNEST F. MECHLIN, OF WASHINGTON, DISTRICT OF COLUMBIA.

DRAFT RIGGING.

Application filed February 4, 1926. Serial No. 86,011.

My invention relates to draft rigging for railway cars and more particularly to mechanism for operatively connecting the coupler to the yoke member.

5 The principal feature of the invention is to provide means for connecting a swivel butt coupler to a hooded yoke of standard A. R. A. dimensions so that the strains incident to the buffing movement of the draft 10 rigging can be uniformly transmitted to the cushioning mechanism irrespective of the radial position of the coupler, a portion of the buffing strain being also received by the yoke through co-acting bearing portions 15 provided on the yoke and coupler stem.

Another object of the invention is to provide an improved construction of draft rigging in which the coupler is pivotally connected to the yoke member so that the draft 20 strains are taken through a pin which is suitably retained by an intersecting key, and the buffing loads transmitted to the cushioning mechanism through a plurality of pivoted members, said members comprising 25 the coupler stem and having co-acting bearing portions which permit relative pivotal movement of the coupler and yoke when engaged as the result of the buffing movement of the draft rigging, some of the bearing 30 portions on the coupler stem being adapted to coact with adjacent bearing portions provided on the yoke whereby buffing strain is transmitted to the yoke as well as to the cushioning mechanism, irrespective of 35 the position of the coupler with relation to the center line of the car.

Another object of the invention is to provide a pivotally connected coupler and yoke mechanism adapted for use with A. R. A. 40 standard draft gear and draft gear pocket, the said yoke being also adapted to permit of the use therein without alteration or change of a standard A. R. A. coupler.

A further object of the invention resides 45 in the production of means for operatively connecting a yoke member to a coupler capable of radial movement with respect to said yoke, said means including a pivot member adapted to unite the coupler and 50 yoke and receive the draft strains, said pivot member being adapted to pass through a plurality of relatively rotatable members intermediate the ends of the yoke, said rotatable members comprising the coupler

stem and being provided with longitudinally spaced bearing portions concentrically disposed with relation to the pivot member and adapted to uniformly transmit buffing loads to the cushioning mechanism of the draft rigging, some of said bearing portions 55 being adapted to co-act with adjacent bearing portions on the yoke, and means including a retaining member adapted to intersect the pivot member, said retaining member being also designed to extend through the 60 slotted portions of the coupler and yoke and being housed within the center sills of the draft rigging.

The invention further consists in the construction of the several elements together 70 with their particular arrangement and combination, as hereinafter set forth.

In the drawings illustrating my invention, the scope whereof is pointed out in the 75 claims:

Figure 1 is a top plan view, partly in horizontal section, illustrating a coupler and yoke member constructed in accordance with my present invention.

Figure 2 is a side view with parts in vertical longitudinal section of the construction shown in Figure 1.

Figure 3 is a horizontal sectional view on the line 3—3 of Figure 2.

Figure 4 is a top plan view with parts in horizontal section, of a railway draft rigging embodying the invention.

Figure 5 is a detail vertical longitudinal sectional view through one of the rotatable coupler members to be referred to herein 90 as the swivel block.

Referring to the drawings in which similar reference characters designate corresponding parts in the several views, I have shown a hooded yoke 1 of the vertical type 95 connected to a swivel butt coupler 2. The coupler stem is of a two-part construction comprising the rotatable or pivoted members 3 and 4, the latter forming the swivel block. The members are each provided with 100 a key slot formed in part in each of the said members, said slot being adapted to receive the transversely disposed key 5. The key 5 is adapted to intersect the pivot member or pin 6 which connects the rotatable members 105 of the coupler stem to opposite side walls of the hooded end of the yoke. The retaining key 5, in addition to maintaining the

pivot pin or pintle in position, provides a safety connection between the coupler and yoke in that should the pin break under service conditions the key, with its respective ends extending into the slotted center sills, will prevent the separation and dropping of the coupler and yoke.

The member 3 of the coupler stem is provided with the spaced rearwardly extending arms or lips 7, the end portions of which are curved or rounded so as to provide the bearing faces 8. Each arm 7 is also provided with a projecting rib or web 9, the inner face of which is curved or rounded concentrically with the face 8 at the rear end of each arm 7. Arranged between the spaced arms 7 of the coupler is the second member or swivel block 4, said block being formed with forwardly projecting arms 10 arranged adjacent the arms 7 and suitably spaced to form the slot which receives the transversely disposed connecting key 5. The ends of the arms 10 are rounded or curved concentrically, as indicated at 11, for operative engagement with the adjacent inner curved faces provided on the projecting webs 9.

The swivel block 4 is provided with an inner portion 12 extending into the hooded end of the yoke and disposed in the nature of a follower which maintains a relatively fixed position for engagement with the cushioning mechanism of a draft rigging, diagrammatically illustrated in dotted lines in Figure 4, irrespective of the radial or swinging movement of the coupler. The outermost face of the portion 12 is rounded or curved concentrically at a plurality of points, as indicated by the numeral 13, said curved face being arranged for cooperative engagement with the curved faces 8 provided on the inner face of the arms 7 of the coupler member 3.

The yoke 1 is formed with a hooded end provided with a plurality of pairs of oppositely disposed side walls, one pair of the side walls being provided with aligned slots 14 and the other pair of side walls being formed with aligned openings 14'. The forward ends of the side walls in which the openings 14' are provided are curved or rounded concentrically with said openings, as indicated by the numeral 15. The curved forward ends 15 provide relatively large bearing portions adapted to co-act with similarly curved bearing surfaces provided on the coupler stem, said last named bearing surfaces being also formed concentrically about the openings 14' and pivot member 60 contained therein. The forward ends 15 of the yoke side walls are united with the inner faces of the yoke arms with sufficient clearance to permit angling of the coupler and that portion formed with the co-acting bearing surfaces. The co-acting bearing surfaces

are formed on projecting webs 16, said webs being suitably reinforced by ribs 17. It will be observed that on buffing movement the coupler stem bearing faces on the webs 16 are brought into engagement with the adjacent bearing surfaces on the curved portions 15 of the walls of the yoke, the contour of the abutting bearing portions permitting relative pivotal action of the coupler and yoke.

In Figure 4 of the drawings I have shown my improved connecting means associated with a draft rigging disposed between the slotted center sills 18, said center sills being provided with front stop members 19 and rear stop members 20 between which is disposed the cushioning mechanism. The coupler is shown connected to the hooded end of the yoke member by means of the pin 6, said pin being formed with a head 21 having a bearing face 22 co-operatively associated with a projecting abutment 23 provided on the yoke. The bearing face and abutment 23 are transversely disposed and, in addition to receiving some of the strains, act to prevent rotation of the pin.

In operation it will be obvious that the draft strains are taken through the connecting pin 6 which is encircled by the arms 7 of the coupler member 3, said pin being placed under quadruple shear but since the pin is suitably braced throughout its entire length all danger of distortion is avoided and sufficient metal provided to withstand all of the strains incident to the draft. Under buffing loads the co-acting bearing surfaces of the rotatable coupler come into operative engagement for transmitting the loads directly to the cushioning mechanism which is positioned in the rear of and in contact with the portion 12 of the swivel block 4. In addition, the co-acting bearing portions on the coupler member 3 and the yoke 1 are also brought into operative engagement whereby a portion of the buffing loads is transmitted to the yoke. The concentric disposition of the co-acting bearing surfaces on the rotatable coupler members and one of the coupler members and the yoke arms permits of relative pivotal movement of the yoke and coupler when engaged as the result of the buffing movement of the draft rigging. As a result of my present construction a strong and reliable connecting means is provided between a swivel butt coupler and yoke member, the several parts being capable of economical manufacture and of dimensions falling within the A. R. A. standards.

I claim:

1. In a railway draft rigging, the combination with a coupler, of a hooded yoke, means pivotally connecting said yoke and coupler, a key intersecting said pivotal means and extending through the yoke and

coupler, and means provided on said coupler and yoke for resisting buffing movement, said means being designed to permit relative pivotal action of the yoke and coupler when in engagement.

5 2. In a railway draft rigging, the combination with a coupler, of a hooded yoke, a pin connecting said yoke and coupler, a key extending at an angle to said pin and adapted to retain the same in position, and means including co-acting bearing surfaces formed on the coupler and yoke for resisting buffing strains, said bearing surfaces being designed to permit relative pivotal movement of the yoke and coupler when in engagement.

10 3. In a railway draft rigging, the combination with a slotted coupler having a bearing surface, of a slotted yoke provided with a co-acting bearing surface, a pin pivotally connecting said coupler and yoke, and a retaining member adapted to intersect said pin and arranged to pass through the slots in said yoke and coupler, the said bearing surfaces on the yoke and coupler being designed to permit relative pivotal movement thereof when they are engaged as the result of the buffing movement of the draft rigging.

15 4. In a railway draft rigging, the combination with a coupler, of a hooded yoke, means pivotally connecting said coupler and yoke, a key extending through said yoke and coupler, and means provided on said coupler and yoke for engagement upon buffing movement of the draft rigging, said means comprising co-acting bearing portions arranged concentrically with respect to said pivotal means for permitting relative swinging movement of the yoke and coupler when engaged as a result of the buffing movement.

20 5. In a railway draft rigging, the combination with a coupler, of a yoke provided with a hooded end, means including a pin pivotally connecting said coupler and yoke, means passing through said coupler and yoke for retaining said pin in position, and means including co-acting bearing surfaces provided on said hooded end and adjacent portions of the coupler, said bearing surfaces being adapted to permit relative pivotal movement of the coupler and yoke when engaged as the result of the buffing movement of the draft rigging.

25 6. In a railway draft rigging, the combination with a coupler having a plurality of bearing portions adapted to transmit buffing strains to the draft rigging, of a yoke having a hooded end provided with a plurality of bearing portions adapted to co-act with the bearing portions on said coupler, a pin pivotally connecting the coupler and yoke, and a draft key intersecting said pin for retaining the same in position, the said co-acting bearing portions of the coupler and yoke being arranged to permit relative

pivotal movement thereof when in engagement as the result of the buffing movement of the draft rigging.

7. In a railway draft rigging, the combination with a coupler having longitudinally spaced bearing portions adapted to transmit buffing strains to the cushioning mechanism of the draft rigging, of a yoke provided with bearing portions adapted to co-act with some of the coupler bearing portions, means including a pivot member adapted to connect said coupler and yoke, and draft means disposed at an angle and adapted to intersect said pivot member for retaining the same in position.

10 8. In a railway draft rigging, the combination with a slotted coupler provided with spaced bearing portions, of a yoke having a hooded end, one pair of walls of which are formed with slots and the other pair of walls of which are provided with bearing surfaces adapted to be engaged by the spaced bearing portions of said coupler upon buffing movement of the draft rigging, means for pivotally connecting said coupler and yoke, and a retaining key intersecting said pivotal means and extending through the slotted coupler and slotted walls of said yoke.

15 9. In a railway draft rigging, the combination with a hooded yoke provided with bearing portions adapted to receive buffing strains, of a coupler stem comprising a plurality of relatively rotatable members, co-operating bearing portions provided on said rotatable members adapted to transmit buffing strains to the draft rigging, other bearing portions provided on one of said rotatable members adapted to co-act with the bearing portions on the yoke, and means for pivotally connecting the yoke and coupler stem.

20 10. In a railway draft rigging, the combination with a hooded yoke provided with bearing portions adapted to receive buffing strains, of a two-part coupler stem having portions thereof pivotally connected at a point intermediate the ends of said yoke member, means formed on one of the coupler portions for engaging a movable element of the draft rigging under movement in one direction, a plurality of co-acting bearing surfaces on said coupler portions concentrically disposed about the pivotal connection thereof, some of said bearing portions being adapted to co-act with the bearing portions on the yoke upon buffing movement of the draft rigging.

25 11. In a railway draft rigging, the combination with slotted center sills, of a swivel butt coupler having means for engaging a movable element of the draft rigging under movement in one direction, a hooded yoke provided with bearing portions adapted to receive buffing strains, a plurality of co-acting bearing portions provided on said

coupler, some of said bearing portions being adapted to co-act with bearing portions on the yoke, and a transversely disposed key intersecting the swivel connection of the coupler, the ends of said key projecting through the slot in the center sills.

12. An integral hooded yoke adapted to receive a standard coupler, said yoke being provided with alined openings having curved 10 end portions in one pair of walls and having bearing portions on each of said walls, said bearing portions being disposed concentrically to the said curved portion of said openings, the other pair of walls being formed 15 to receive a draft key.

13. A hooded yoke adapted to receive a standard coupler, one pair of walls of said yoke being slotted to receive a key and the other pair of walls being adapted to receive 20 a pivotal connection, and bearing portions provided on the end portions of the pair of walls receiving the pivotal connection and adapted to receive forces from the coupler.

14. A coupler stem comprising a plurality

of pivotally connected members provided 25 with a key slot formed in part in each of said members, co-acting bearing portions provided on said members and arranged concentrically of the pivotal connection, and a bearing portion projecting from at least 30 one of said members, said bearing portion being concentrically arranged with respect to the pivotal connection and adapted to engage an adjacent bearing portion on a standard yoke. 35

15. In a railway draft rigging, the combination with a hooded yoke, of a coupler stem comprising a plurality of relatively rotatable members, cooperating bearing portions provided on said rotatable members, said 40 portions being adapted to transmit buffing strains to the draft rigging, said relative rotatable members being intersected by a slot, and a key passing through said slot and the adjacent portion of said yoke for operatively 45 connecting said coupler and yoke.

In testimony whereof I affix my signature.
ERNEST F. MECHELIN.
